MAX HADAM, OF CHEMNITZ, GERMANY, ASSIGNOR TO FIRMA MASCHINENFABRIK
KAPPEL, OF CHEMNITZ-KAPPEL.

EMBROIDERY MACHINE.

Application filed September 3, 1925, Serial No. 54,325, and in Germany September 9, 1924.

This invention relates to improvements in embroidery machines of the type in which the work is mounted in a frame, the horizontal and vertical movements of which, at 5 each stitch, are controlled from a jacquard pattern card and the invention is more particularly directed to the mechanism by which the constant movement of a driving member is transmuted into a desired variable movement of the work frame setting rack in accordance with the pattern to be embroidered.

In machines of this kind, it has already been proposed to employ a series of levers or a combination of toothed wheels, levers and worm gear which effected the desired result. In one known construction, a series of toothed wheels are selectively clutched, by jacquard controlled mechanism, so as to make a half revolution and thereby operate 20 selected levers or a selected lever for transmitting a greater or lesser movement to the frame operating rack. In this construction the toothed wheels are moved sidewise from the jacquard selecting device and the entire 25 mechanism is apt to give an inaccurate result owing to wear of the teeth as well as to varying elasticity or flexibility of the lever structure which is interposed between the toothed wheels and the frame rack. In 30 a continuous lever structure, having equal armed double levers, in which the end of one lever is articulated to the centre of the next, there is only one fixed point in the lever system, which consequently has an undesirable 35 degree of elasticity leading to inaccuracy and irregularity of setting of the work frame. In these systems, as in the present invention, the frame is moved through a selected number of "units", the maximum 40 number of units of any movement being about 60.

According to the present invention, the stitch adjusting device is composed of a series of interconnected levers, forming the 45 chain of levers for transmuting the constant movement of the driving member into a variable movement of the work frame rack, by selectively moving or holding stationary the intermediate point pivots of said levers. 50 The members which move the intermediate point pivots of the levers of the chain are themselves levers and the main feature of novelty of the present invention resides in

the fact that the fulcrums of these adjusting levers are fixed points, being conveniently mounted in the machine frame or in brackets fixed to the machine frame. The result of this arrangement is that, at all possible settings of the device, a high degree of rigidity is obtained with consequent accuracy and without the need of toothed wheels. The adjusting levers, that is the members which move the pivot points of the lever chain, are operated by rods having clutch members which are either in engagement with a fixed bar, so as to hold the given 55 adjusting lever stationary or in engagement with the driving member which executes a constant movement. The selection as to whether the rods engage with the fixed bar 60 or with the constant driving member is made by the feeler pins which are controlled by the jacquard pattern card. These pins operate to set the butts of sliding jacks in such positions that they either intercept, or 65 do not intercept, fall levers articulated to the operating rods. A fall lever when so intercepted by the butt of a jack, places the operating rod to which it is articulated in operative engagement with the constant 70 movement driving member. The fall levers not so intercepted allow their operating rods to engage with the fixed bar, whereby the corresponding adjusting levers are held stationary.

The invention will be more readily understood from the following description of the form shown in the accompanying drawings which show in diagrammatic form, the chain or system of levers together with the adjusting levers and the train of mechanism interposed between the jacquard pattern card and the adjusting levers.

It has not been considered necessary to illustrate the entire machine, but only so 95 much as is required to explain the operation of the present invention. The remainder of the structure, the duplication necessary for horizontal as well as vertical movement of the work frame, the frame reversing mechanism and the other stitch controls which may be used are disposed in the manner known in such machines and will be readily understood by those engaged in this art.

The work frame is operated from a rack 105 26 which is moved backwards and forwards

at each stitch by a predetermined amount, which is varied in accordance with the stitch required at the particular part of the pattern under execution. The rack 26 is always 5 returned at the completion of each stitch to its initial position. This rack is of box form and is provided with two sets of teeth at 26^a and 26^b and embraces a pinion 55, with one or other of these sets of teeth in engagement with the pinion, according to the setting of the rack 26. In accordance with which set of teeth, 26^a or 26^b, is engaged, the pinion 55 is rotated in one or other direction. By the known means the rotary movement 10 of the pinion 55 is transmitted as a linear movement to the work frame. The reversal of the pinion is effected by swinging the box rack 26, by means of the lever 26^c, which is suitably controlled in the well 15 understood manner by two rows of holes in the jacquard pattern card 45.

The constant movement of the driving member is effected from the cam 46 which operates a rod 47 coupled to two bell crank 20 levers 48 and 49. The bell crank levers 48 and 49 are operated at each stitch to swing to and fro over the angle indicated by dot and dash lines. The mechanism interposed between the rack 26 and the constant drive 25 mechanism embodied by the levers 48 and 49 constitute the subject matter of this invention. By means of this interposed mechanism, the constant movement of the bell crank levers 48 and 49 is transmuted into a 30 movement of any desired multiples of a predetermined unit up to a total of 63 units.

The levers 1, 2, 3, 4, 5, 6, constitute a double series and are the adjusting levers, each of which has a fixed fulcrum. The levers 40 1, 2, 3 have their fixed fulcrums 7, 8, 9 at one end, whilst the parallel series of adjusting levers have their fixed fulcrums 10, 11 and 12 at an intermediate point such that the two arms are unequal. The ratio of 45 these arms may be arranged in accordance with the desired length of a "unit" of movement of the work frame. On the adjusting levers there are pivoted at intermediate points, in the ratio of two to one, levers 13, 50 14, 15, 16, 17, 18, which are interconnected at their ends to form a chain of levers in series, by means of connecting rods or links 19, 20, 21, 22, 23, 24. The rod 19 at one end of this chain is anchored to a fixed pivot 55 25 and the short arm of the lever 18 at the other end of the chain is connected to the rack 26 for setting the work frame. If desired the ratio of the arms of the levers 13 to 18, may be other than that shown, viz, 60 2:1.

It will be seen that the levers of the chain 13-18 are so interconnected that the short arm of one lever is articulated to the long arm of the next following.

65 The adjusting levers 1, 2, 3 are articulated

at their free ends to the connecting rods 27, 28, 29, whilst the long arms of the levers of the parallel series 4, 5 and 6 are articulated to the rods 30, 31, 32. Each of the rods 27-32 has at its left hand end in the figure 70 two opposite hook openings 33 and 34 and to the left of these openings each rod has a tail piece 35. Springs 36 pull the tail pieces downwards so that these tails rest on the fall rods 37 and 38. These two sets of rods 75 appear in the drawing to be in the same plane, but the fall rods 37 are long and extend to the tails 35 of the rods 27, 28, 29, whilst the fall rods 38 are short and extend only to the tails 35 of the lower series of rods 80 30, 31, 32. The fall rods 37 and 38 have projections 39 lying over a bar 41 on a swing lever 40. After each stitch, the bar 41 lifts all the fall rods, whereupon the jacquard card 45 is moved forward in the known 85 manner through one step so as to bring a new transverse row of holes opposite the feeler pins 44. The card frame is then swung from left to right in the figure in the ordinary manner, so that the feeler pins 44 90 pass through the holes in the card, if there is a hole opposite, or are pushed to the right if no hole is opposite. In this way the particular selection of feelers and ultimately of adjusting levers 1-6 is made.

The feeler pins 44 are carried by suitably guided sliding jacks 42, having butts 43. When no hole in the pattern card is opposite any given feeler pin 44, the butt of its jack 42 is pushed to the right, as indicated 95 at 43' and when there is a hole opposite the feeler pin, the butt remains stationary in the position indicated at 43. The swing lever 40 now drops the fall levers 37, 38 so that some will drop into the lower positions and others will be interfered with or intercepted by the butts 43 which have remained stationary. In this way any single one or any combination of the rods 27-32 may be held 100 up so that the upper openings 33 are in engagement with the driving pins 50 of the lever 48 or the pin 51 of the lever 49. In the position illustrated the rods 27, 29 and 30 are held with their openings 33 in operative engagement with the driving members 105 48 and 49, whichever applies. Those rods (28, 31, 32 in the selection illustrated) whose jacks 42 were moved back with their butts as at 43', drop with their fall rods so that the lower openings 34 engage over fixed 110 bars 52 in the case of the upper series and 53 in the case of the lower series. After the operation of the rods 27-32, the swing lever 40 again raises the fall levers 37, 38 and a lever 54 returns the jacks 42 so that the 115 row of feeler pins 44 is in condition to receive the next selection. The jacquard mechanism described is substantially of known form and does not in itself constitute a 120 novel feature of this invention, but its de- 125 130

scription is necessary in order to explain the selective operation of the adjusting levers 1—6, the operation of which is as follows:

- 5 When the rod 27 with adjusting lever 1 is moved to the right, as indicated by dot and dash lines, the frame setting rack 26 is moved to the left by a single "unit", provided none of the other adjusting levers is operated. If only the adjusting lever 4 is moved, the frame setting rack 26 receives a movement of two "units". If the lever 2 is moved by its rod 28, the rack 26 receives a movement of 4 "units". The individual 10 values in "units" of the movements effected by the separate levers may be tabulated as follows:

If lever 1 only is selected, rack 26 moves 1 unit.

20 If lever 4 only is selected, rack 26 moves 2 units.

If lever 2 only is selected, rack 26 moves 4 units.

If lever 5 only is selected, rack 26 moves 25 8 units.

If lever 3 only is selected, rack 26 moves 16 units.

If lever 6 only is selected, rack 26 moves 32 units.

30 The movement values of all the levers selected, when a combination of more than one is rendered operative by the jacquard pattern card, are as will be understood, summed up in the movement of the final 35 lever 18 of the chain and by it transmitted to the frame setting rack 26. If all the adjusting levers 1—6 were operated, the movement of the lever 18 would be equal to the sum of the "units" column above, that is 63 40 units. With the selection indicated in dot and dash lines, levers 1, 4 and 3 have been selected, so that the movement of the frame setting rack 26, will in this case be:—

45 $1+2+16=19$ units from right to left.

With this organization of the lever system, it will be recognized that the six pivot points, of the chain levers 13—18 are definite basic points by virtue of their location on 50 the adjusting levers 1—5, which are provided with the fixed fulcrums 7—12 and are "fixed" not as regards actual movement, but in the sense that their distance from the fixed fulcrums 7—12 is a fixed definite distance. The elasticity which can enter this 55 structure is thus limited to the variation which can enter betwixt two adjacent adjusting levers, such as between the adjusting lever 2 and lever 5, or between levers 5 and 60 3 or 3 and 6. Any errors which may creep in can only be exceedingly small and the system cannot act accumulatively on such errors. The smallest values of unit movements are transmitted from the left hand in 65 the chain of levers and of necessity has to

pass through the whole chain, so that the elimination of elasticity in the chain is of especial importance for such movements. This rigidity results from the distribution along the series, that is at intervals along 70 the chain of levers, 13—18, of the fixed fulcrums 7, 8, 9, 10, 11 and 12. It will further be seen that the bending moment applied by each chain lever to its adjusting lever is incident at a point nearer the fixed 75 fulcrum than the connection of the adjusting lever to the operating rods 27—32. This also assists in contributing rigidity to the transmission chain.

I claim:

1. In an embroidery machine having a jacquard card mechanism, a constant movement driving member, and a variable movement work frame rack, transmuting means 80 interposed between the constant movement driving member and the variable movement work frame rack, comprising operating rods controlled from the jacquard card mechanism, an adjusting lever for each operating rod, pivoted thereto and having a fixed fulcrum, and an interconnected chain of levers pivoted on said adjusting levers and pivotally connected at one end of the chain to a fixed fulcrum and at the other end to the work frame rack.

2. In an embroidery machine having a jacquard card mechanism, a constant movement driving member, and a variable movement work frame rack, transmuting means 85 interposed between the constant movement driving member and the variable movement work frame rack, comprising two sets of operating rods controlled from the jacquard card mechanism, an adjusting lever for each operating rod of one set pivoted thereto and having a fixed fulcrum at one end, an adjusting lever for each operating rod of the other set pivoted thereto and having a fixed 90 fulcrum located intermediately of its length, and an interconnected chain of levers pivoted on said adjusting levers and pivotally connected at one end of the chain to a fixed fulcrum, and at the other end to the work frame rack.

3. In an embroidery machine having a 115 jacquard card mechanism, a constant movement driving member, and a variable movement work frame rack, transmuting means interposed between the constant movement driving member and the variable movement work frame rack, comprising two sets of operating rods controlled from the jacquard card mechanism, an adjusting lever for each operating rod of one set, pivoted thereto and having a fixed fulcrum at one end, an 120 adjusting lever for each operating rod of the other set, pivoted thereto and having a fixed fulcrum located intermediately of its length, the adjusting levers of each set being 125 parallel and the sets arranged alternately. 130

and an interconnected chain of levers pivoted on said adjusting levers and pivotally connected at one end of the chain to a fixed fulcrum and at the other end to the work frame rack.

4. In an embroidery machine having a jacquard card mechanism, a constant movement driving member, and a variable movement work frame rack, transmuting means interposed between the constant movement driving member and the variable movement work frame rack, comprising two sets of operating rods controlled from the jacquard card mechanism, an adjusting lever for each 15 operating rod of one set, pivoted thereto and having a fixed fulcrum at one end, an adjusting lever for each operating rod of the other set pivoted thereto and having a fixed fulcrum located intermediately of its length, 20 the adjusting levers of each set being parallel and the sets arranged alternately, and further levers pivoted at points intermediate of their length to said adjusting levers and connected at their ends to form a chain of 25 levers, one end of said chain being pivoted

to a fixed fulcrum and the other end to the work frame rack.

5. In an embroidery machine having a jacquard card mechanism, a constant movement driving member, and a variable movement work frame rack, transmuting means interposed between the constant movement driving member and the variable movement work frame rack, comprising two sets of operating rods controlled from the jacquard card mechanism, an adjusting lever for each 30 operating rod of one set, pivoted thereto and having a fixed fulcrum at one end, an adjusting lever for each operating rod of the other set pivoted thereto and having a fixed 35 fulcrum located intermediately of its length, further levers pivoted at intermediate points to said adjusting levers and having long and short arms, and connecting links from the short arm of one lever to the long 40 arm of the next so as to form a chain of levers, one end of said chain being pivoted to a fixed fulcrum and the other end to the 45 work frame rack.

MAX HADAM.
